STABILIZED VESICANT AGENT

William H. Wood, Arden, Del., assignor, by mesne assignments, to the United States of America as represented by the Secretary of War

No Drawing. Application December 11, 1945,
Serial No. 634,408

3 Claims. (Cl. 167—47)

1

This invention relates to the stabilization of mustard gas and more particularly deals with the stabilization of iron contaminated mustard gas which has been, or, is to be, thickened by the addition of a thickening agent.

This invention particularly relates to the stabilization of thickened iron-containing "Levinstein" mustard gas.

Mustard gas hereinafter called "mustard" is the most important Chemical Warfare vesicant agent. Chemically, pure mustard is bis-(beta-chlor ethyl) sulfide. There are several methods for manufacturing mustard but the most important, in this country, is the "Levinstein" process. The product of this process is known to those skilled in the art as "Levinstein" mustard.

Levinstein mustard is a relatively impure product and the dichlorethyl sulfide content thereof is in the neighborhood of 70%. The impurities in Levinstein mustard are of a complex nature and have not yet been completely determined to this date but are essentially polysulfides of the composition $(ClCH_2CH_2)_2Sx$.

Levinstein mustard is a very effective vesicant agent and is economical for use in chemical warfare, however, it does have the serious defect of attacking steel containers during long periods of storage. Although the exact mechanism of the chemical reaction between Levinstein mustard and steel containers is not known, it is known that mustard, stored in steel containers, becomes contaminated with iron. Levinstein mustard stored in glass containers, or in steel containers coated with a properly baked-on suitable lacquer, does not deteriorate.

For certain technical purposes it is necessary to disseminate vesicants such as mustard from airplanes. Heretofore, the effectiveness of the vesicants when sprayed from airplanes has been considerably less than the maximum effectiveness obtainable, because a large portion of the vesicant material is broken up into a very fine mist and a correspondingly smaller fraction reaches the objective in the form of large drops. The higher the altitude and the greater the airplane speed, the greater is the proportion of the fine mist and the less effective the vesicant spray.

Vesicant agents in liquid form are most effective against personnel and material in the form of fairly large drops and the loss of effectiveness of airplane sprays due to the formation of fine mist is very considerable. Vesicants in the form of fine mists have a decreasing penetrating action through protective clothing and a smaller amount of protection is required against them. Heretofore, it was necessary for an airplane to drop to very low altitudes (75-500 ft.) and to spray at a low air speed to obtain proper sized drops in a vesicant spray.

Another very important obstacle in the spraying of vesicants from airplanes has been the

2

inability to aim the spray to fall upon the target with any degree of accuracy. Vesicant sprays in the form of relatively large drops can be accurately aimed but fine sprays and mists fail to hit the target area with any degree of precision.

The same general principles also apply to the dissemination of vesicants by artillery shell. The use of high explosive charges to burst the shell results in the creation of a fine mist and consequent dispersion of the vesicant.

It has therefore been found to be necessary to thicken the vesicant agents in order to obtain proper drop size and to eliminate the loss of agent, the loss of accuracy, and the necessity for projecting the spray from low altitudes at low plane speeds. The addition of certain polymeric materials to vesicant agents in order to thicken the agent to obtain the required properties has been proposed. However, I have discovered that vesicant agents thus thickened have the defect of decreasing in viscosity when the agent is contaminated with iron.

I have discovered that in iron-contaminated mustard containing a polymeric thickener there is formed a complex of low solubility between the polymeric thickener and the iron, which precipitates and lowers the viscosity of the supernatant mustard below that required for its dissemination in proper drop size.

Since mustard is normally stored in steel containers both before and after thickening, contamination with iron, always occurs and lowering of viscosity due to the above described reaction is encountered.

I have discovered that this serious defect can be remedied by the addition of certain stabilizers to the mustard either before or after thickening, in order to prevent the precipitation of the iron-thickener complex and to thus maintain the desired viscosity of the vesicant agent.

I have found that heterocyclic aromatic nitrogen bases of any degree of purity are suitable as stabilizers for thickened mustard.

Any of the crude aromatic nitrogen bases or fractions of crude bases obtained from coal tar or petroleum, or pure bases such as pyridine, quinoline, and picoline may be used. Ordinarily, an amount of nitrogen base equal to 2% of the weight of the mustard is sufficient. This amount will neutralize all the iron in mustard containing up to 1% iron, calculated as ferrous chloride. If more than 1% iron is present, proportionally larger amounts, e. g., up to 5% of nitrogen bases, may be used. When mixing in the plant, it is preferable to add the nitrogen base to the mustard first, to prevent precipitation of the iron-thickener complex when the thickener is added. When mixing in the field, the nitrogen base may be added either to the thickener solution or to the mustard, the thickener and mustard then being combined. Whatever the mixing method em-

ployed, the nitrogen base may be added either to the thickener solution or to the mustard, the thickener and mustard then being combined. Whatever the mixing method employed, the nitrogen base may be used in conjunction with non-aromatic amines, such as hexamethylene-tetramine, which are effective anti-corrosion agents for mustard. These nitrogen bases have been tested in mustard, thickened with methyl methacrylate polymer and methyl methacrylate-methyl acrylate interpolymer, and they are also effective in mustard containing any other polymeric thickener, e. g., polystyrene.

This invention contemplates compositions comprising iron-contaminated mustard containing a polymeric thickener soluble therein, and a small amount of a heterocyclic aromatic nitrogen base, i. e., a nitrogen base in which the nitrogen is part of an aromatic ring, i. e., a ring containing conjugated double bonds. Nitrogen bases of this type have been found to be particularly effective in preventing the iron normally present in ordinary mustard (particularly that stored in steel containers) from altering, undesirably, the viscosity characteristics of the thickened composition. This is of significance since, if the iron is not removed or deactivated, it will form a complex of low solubility with the polymeric thickener and precipitate as a sludge, particularly at low temperatures. The precipitation of the iron-thickener complex removes the thickener and thus lowers the viscosity of the supernatant mustard below that necessary for its dissemination in the desired droplet size. Typical compositions and their preparation are illustrated by the following examples, in which parts are by weight.

Example I.—Field-mixing process

A steam-jacketed iron vessel fitted with a reflux condenser and mechanical stirrer is charged with 652 parts of benzene and 87 parts of quinoline residue (from distillation of quinoline from coal tar—contains high boiling nitrogen bases of quinoline type), and 33 parts of pulverized methyl methacrylate polymer sheeting are added with stirring. The temperature of the mixture is raised to 50-55° C. and agitation continued at this temperature until a product of constant viscosity is obtained, about 4 to 5 hours being required. This solution, which will have a viscosity in the range of 8 to 25 stokes at 25° C., is suitable for mixing with mustard in the field. In the case of Levinstein mustard containing, e. g., 0.5-0.6% iron (calculated as ferrous chloride), 15 parts of the solution is added to 85 parts of mustard and the mixture agitated gently for 15-20 minutes at room temperature. The resulting smooth solution has a viscosity of about 0.42 stoke at 10° C. with no sludge formation, while the same mustard thickened with the same proportion of polymeric methyl methacrylate but containing no nitrogen base has at 10° C., due to precipitation of polymer-iron complex, a viscosity of only 0.065 stoke, which is too low for proper dissemination of the mustard.

Example II.—Plant mixing process

A vessel equipped with a mechanical stirrer and means for heating is charged with 1586 parts of mustard of the quality used in Example I, 32 parts of a mixture of pyridine bases, and 32 parts of pulverized methyl methacrylate polymer sheeting are added. The mixture is stirred at 40 to 50° C. for 3 hours, then cooled to room

temperature and stirred overnight. The resulting smooth solution has a viscosity of 4.44 stokes at 10° C., with no sludge formation, whereas a control composition containing no pyridine base forms a sludge immediately when cooled to 10° C.

Attempts have been made to stabilize thickened Levinstein mustard by the addition of a non-aromatic heterocyclic amine but the results were not satisfactory. The only amines which I have found to be effective for this purpose are the heterocyclic aromatic nitrogen basis which contains a conjugate double bond system.

Accordingly, an object of my invention is to stabilize thickened mustard gas in order to maintain proper viscosity. Another object of this invention is to provide a practical and effective means of stabilizing Levinstein mustard so that it can be thickened and so that the viscosity of the thickened agent can be controlled in order that proper drop size may be obtained upon dissemination of the agent.

My invention, by the addition of a small amount of a heterocyclic aromatic amine, prevents the precipitation of iron-thickener complex and thus maintains the desired viscosity of agent.

The nature of this invention having been broadly outlined above and the preferred embodiments specifically pointed out, it will be apparent to those skilled in the art that certain modifications and additional formulations can be employed. Accordingly, it is intended that the foregoing descriptive material be interpreted as illustrative and not in a limiting sense.

I claim:

1. A composition of matter comprising Levinstein mustard containing from about 0.5% to 0.6% of iron calculated as ferrous chloride, thickened with a polymeric material selected from the group consisting of methyl methacrylate polymers and of methyl-methacrylate-acrylate interpolymers and stabilized with from about 2% to about 5% of a compound selected from the group consisting of pyridine, quinoline and picoline, said composition having a viscosity of about 0.42 stoke at 10° C. with no sludge formation.

2. A composition of matter comprising about 85 parts by weight of Levinstein mustard containing about 0.5-0.6% of iron calculated as ferrous chloride; thickened and stabilized with about 15 parts by weight of a solution having a viscosity in the range of 8 to 25 stokes at 25° C. and consisting of 652 parts by weight of benzene, 87 parts by weight of quinoline residue, and 33 parts of methyl methacrylate polymer, said composition of matter having a viscosity of about 0.42 stoke at 10° C. with no sludge formation.

3. A composition of matter comprising about 1586 parts by weight of Levinstein mustard containing about 0.5-0.6% of iron calculated as ferrous chloride, about 32 parts by weight of pyridine bases, and about 32 parts by weight of methyl methacrylate polymer, said composition of matter having a viscosity of about 4.44 stokes at 10° C. with no sludge formation.
